(57) **CLAIM**

The ornamental design for an adjustable clamping square, as shown and described.

DESCRIPTION

FIG. 1 (FIG. 1) is a front, top, right side isometric perspective view of a first embodiment of an adjustable clamping square in accordance with my design.

FIG. 2 (FIG. 2) is a rear, bottom, left side isometric perspective view of adjustable clamping square as shown in FIG. 1.

FIG. 3 (FIG. 3) is a front elevation view of adjustable clamping square as shown in FIG. 1.

FIG. 4 (FIG. 4) is a rear elevation view of adjustable clamping square as shown in FIG. 1.

FIG. 5 (FIG. 5) is a right side elevation view of adjustable clamping square as shown in FIG. 1.

FIG. 6 (FIG. 6) is a left side elevation view of adjustable clamping square as shown in FIG. 1.

FIG. 7 (FIG. 7) is a top plan view of adjustable clamping square as shown in FIG. 1.

FIG. 8 (FIG. 8) is a bottom plan view of adjustable clamping square as shown in FIG. 1.

FIG. 9 (FIG. 9) is a front, top, right side isometric perspective view of adjustable clamping square in an alternative position.

FIG. 10 (FIG. 10) is a rear, bottom, left side isometric perspective view of adjustable clamping square as shown in FIG. 9 provided in the alternative position.

FIG. 11 (FIG. 11) is a front, top, right side isometric perspective view of a second embodiment of an adjustable clamping square in accordance with my design.

FIG. 12 (FIG. 12) is a rear, bottom, left side isometric perspective view of adjustable clamping square as shown in FIG. 11.

FIG. 13 (FIG. 13) is a front elevation view of adjustable clamping square as shown in FIG. 11.

FIG. 14 (FIG. 14) is a rear elevation view of adjustable clamping square as shown in FIG. 11.

FIG. 15 (FIG. 15) is a right side elevation view of adjustable clamping square as shown in FIG. 11.

FIG. 16 (FIG. 16) is a left side elevation view of adjustable clamping square as shown in FIG. 11.

FIG. 17 (FIG. 17) is a top plan view of adjustable clamping square as shown in FIG. 11.

FIG. 18 (FIG. 18) is a bottom plan view of adjustable clamping square as shown in FIG. 11.

FIG. 19 (FIG. 19) is a front, top, right side isometric perspective view of adjustable clamping square in an alternative position; and,

(Continued)

FIG. 20 (FIG. 20) is a rear, bottom, left side isometric perspective view of adjustable clamping square as shown in FIG. 19 provided in the alternative position.

The broken lines illustrate portions of the adjustable clamping square which form no part of the claimed design.
